MEANS FOR FEEDING FUEL TO INTERNAL COMBUSTION ENGINES OF THE HIGH COMPRESSION TYPE

Application filed September 23, 1924. Serial No. 739,249.

This invention relates to means for feeding fuel to an internal combustion engine of the high compression type, that is to say, an engine in which air is taken into the working cylinder and compressed by the piston therein so that the high temperature developed is sufficient to ignite the fuel which is injected at the proper time from a compression chamber in which fluid products of combustion are trapped and then compressed for the purpose of injecting the fuel that is passed into the compression chamber or a fuel depository therein.

The objects of this invention include means for obtaining a high compression engine of great flexibility, that is to say, one that is responsive to adjustments arranged to vary the speed and power of the engine.

Another object is to obtain an engine which is adapted to use fuel having a low specific gravity such as kerosene, or distillate, although, it is to be understood that it is not limited to one particular type of fuel.

Another object of my invention is to provide an engine which is relatively easy to start, yet positive in its starting operations.

Other objects will be apparent to one skilled in this art.

In order to carry out the objects of my invention, I utilize the fundamental idea of trapping some of the fluid products of combustion in a compression chamber, preferably closely adjacent the main cylinder and then after passing the fuel to the compression chamber, or a fuel depository therein, to compress the products of combustion, and at the proper time in the cycle to connect the compression chamber with the main cylinder, whereby the fuel is injected into the said main cylinder.

Since my Patent #1,305,533, issued June 3, 1919, discloses the idea of using fuel products of combustion for fuel injection purposes, my present invention is directed to an improved form and specific arrangement for

feeding fuel to the engine cylinder through the utilization of fluid products of combustion.

My present invention will be best understood by reference to the attached drawings, 50 wherein

Figure 1 is a part sectional view through the engine showing my improvement.

Figure 2 is a part sectional view at right angles to Fig. 1, the section being taken 55 through the fuel plug and compression chamber also showing the cam arrangement and

Figure 3 is a top view of the fuel plug with the cover removed.

Referring now to details wherein like numbers refer to corresponding parts in the various views, 1 is an engine cylinder having a piston 4 therein. The piston 4 is connected by a connecting rod 3 to a crank shaft 2 which carries the usual fly wheel not shown. The piston 4 has the usual piston rings 5 and the cylinder 1 a water jacket 6. The engine illustrated is of the two cycle type having an exhaust port 7, the air intake not being shown, although, a by-pass 8 is indicated for passing the air, which is compressed in the crank case to the cylinder when the piston is at substantially the lowest part of the stroke. The piston 4 has a part 9 cut away to deflect air from the exhaust port as the air comes from the by-pass 8. The pocket 12 is formed in the upper part of the cylinder when the piston is in its position of the highest compression. The valve 10 held in position by a spring 11 is used in the head of the cylinder for the purpose of relieving compression at the time of starting the engine. Attached to the end of the cylinder, and in any satisfactory manner, as by bolts 12' is a fuel plug 13, and arranged

preferably tandem with the plug 13 is a compression plunger 14, the upper end of which is shaped at 15 to form a fuel depository. It will be seen that between the end of the plug 13 and the end of the plunger, or fuel depository 15, there is formed a compression 85 90

chamber. As indicated in the drawings, the plunger 14, preferably works in a sleeve 16 constructed of suitable material and a gasket 17 is placed between the end of the plug 13 and the sleeve 16. Extending longitudinally 5 of the plunger 14 from the depository 15 is a passage-way 18, and from the passage-way 18, and substantially near the bottom thereof is a cross bore 19. When the plunger is in the position shown in Fig. 1, the cross hole or bore 19 is then in alignment with an opening 20 through the engine or the sleeve 16 which establishes communication between the compression chamber and the pocket 12. The 10 sleeve 16 is also provided with a hole or passage 46 which communicates with the upper part of the pocket 12. The purpose of this hole will be later described.

By reference to Fig. 2, the relative position 20 between the cam 21 and the compression plunger 14, will be seen. The compression plunger 14 is held in proper position through the medium of the aligning pin or screw 22, the end of which operates in a slot 23, so that 25 the alignment of the passages 19 and 20 will be assured. The lower end of the plunger 14 is surrounded with packing 24, held in position by a gland 25. A spring 26 is used to return the plunger 14, after the compression 30 stroke has been completed, through the medium of the cam 21. The end of the fuel plug 13 is preferably provided with a bushing 27 in which is seated a control valve 28 which is held by a spring 29 so as to normally close 35 the opening into the compression chamber. The upper end of the plug 13 terminates in an enlarged portion forming a chamber 30. Extending into the chamber, from the body of the plug, is an injection plunger 31, normally held in upward position by a spring 32. On the end of the injection plunger 31 is positioned the end of the lever 33, the other 40 end of which preferably engages through a socket connection with the end of a push rod 34, the other end of the push rod having operative engagement with a pivoted lever 35 and is actuated by a cam 36. A fuel cavity 37 is formed between the ends of the plunger 31 and the valve 28; the fuel cavity 37 is connected by passage-ways 38 and 39 with the fuel chamber 30. An adjustable valve 40 is carried in the body of the plug so that the inner end is positioned in the passage-way 38 and controls the orifice of this passage leading 50 into the opening 39. The purpose of this arrangement will be presently described. A fuel intake pipe is fitted into the opening 41, leading to the fuel chamber and an over-flow pipe is adapted to be connected by the point 55 42 to the fuel chamber, the level of the fuel chamber being approximately as indicated by the dotted line 43. The manner of feeding fuel to the chamber 30 will not be further described herein as any satisfactory means may 60 be utilized. The chamber 30 is covered by a

cover plate 44 through the medium of screws entering the screw holes 45.

In operation, the position of the main working piston and the compression plunger are shown at about the time when the fuel 70 is being injected into the engine cylinder. Of course, it is to be understood, that the plunger 14 may be timed with respect to the main working piston so that the fuel is injected into the cylinder to give the maximum power from the engine. Assuming that the parts shown in Fig. 1, are in the position as stated fluid products of combustion, which are compressed in the compression chamber, 75 force the fuel from the depository 15, formed in the upper end of the compression plunger 14 through the bore 19 and the opening 20, into pocket 12 where fuel is ignited by the highly compressed air therein. As the cycle 80 of operation continues, and the cam 21 reaches the point 47, the plunger 14, moves downward until the upper end thereof uncovers the port 46, which port is held uncovered until approximately the point 48, on the cam is reached, when the cam produces a slight upward movement of the plunger 14 thereby closing the port 46. During the interval of time, the cam is moving from point 85 47 to point 48, fluid products of combustion at a relatively low pressure, as compared with the pressure directly after ignition 90 takes place, are passed into the compression chamber and when the point 48 of the cam is reached, the compression chamber is cut off from the working cylinder.

During the interval of the time that products of combustion are being trapped in the compression chamber, it will be seen by referring to Fig. 2, that the cam 36 produces an injection of fuel into the compression 105 chamber which fuel is received by the fuel depository formed at the end of the compression plunger 14. This injection of fuel takes place in substantially the following manner: it being understood that the fuel cavity 37 is filled with fuel coming through the passages 38 and the orifice or passage 39, in which the end of the needle valve 40 is positioned. As the cam 36 suddenly forces the push rod 34 upward the lever 33, is actuated to force the injection plunger 31, downward, suddenly raising the pressure in the fuel cavity 37 to such a point that the control valve 28 opens sufficiently to pass a definite quantity of fuel into the compression chamber. The amount of pressure which can be built up in the fuel cavity 37 and likewise the amount of fuel passed to the compression chamber, is controlled by the adjustment of the needle 40, which regulates the size of the by-pass opening by the end of the needle valve. From the point 48 to about the point 110 49 there is substantially no movement of the compression plunger 14, which only begins to move rapidly upward at and in proper 115 120 125 130

timed relationship with the main piston as has been previously described.

It will be apparent that various changes may be made in the details, for example, an auxiliary opening may be provided from the fuel chamber 30 to a point closely adjacent to the end of the plunger 31 whereby fuel may be passed into the fuel cavity 37 directly, this auxiliary opening being shut off by the downward movement of the plunger 31; consequently, I do not wish to be limited to the specific details shown and described herein, except as limited by the scope of the appended claims.

Having thus described my invention what I claim is:

1. In an internal combustion engine, having a main cylinder and a piston therein, means for feeding fuel to said cylinder including; a compression chamber having a plunger therein with means for actuating said plunger in proper time with respect to said piston, said plunger having a longitudinal passage and a cross bore leading from said passage to the periphery of said plunger, said engine having two passage-ways, one in alignment with the cross bore in the plunger when the plunger is at the end of its compression stroke, and the other opening into the compression chamber when the plunger is at the end of its non-compression stroke whereby fluid products of combustion may enter the compression chamber, the end of said plunger acting as a fuel depository 30 and means for injecting fuel into said plunger depository at the proper time as described.

2. In an internal combustion engine having a main cylinder and a piston therein, means for feeding fuel to said cylinder including; a compression chamber having a plunger therein with means for actuating said plunger in proper time with respect to said piston, said plunger having a longitudinal passage and a cross bore leading from said passage to the periphery of said plunger, said engine having passage-way in alignment with said cross bore in the plunger when the plunger is at the end of its compression stroke and at least one other passage-way opening into the compression chamber when the plunger is substantially at the end of its non-compression stroke whereby fluid products of combustion enter the compression chamber, and means for passing fuel into said compression chamber at the proper time as described.

3. In an internal combustion engine of the class described, means for feeding fuel to the engine cylinder including an injection plug and a compression plunger having a fuel depository and a compression chamber between the two of them, said plug provided with a spring-controlled valve and a positively actuated plunger forming a fuel chamber between them communicating with the

compression chamber through a passage-way leading thereinto and controlled by said valve, and operating mechanism to actuate the plunger to compress the fuel in the fuel chamber rearwardly of the valve to open the valve to discharge the fuel into the compression chamber.

4. In an internal combustion engine of the class described, means for feeding fuel to the engine cylinder including an injection plug and a compression plunger arranged co-axially to and in tandem therewith so as to form a compression chamber between the two of them, said plug carrying a fuel pressure control valve opening into the compression chamber and timed operating mechanism for building up fuel pressure on the side of the valve opposite the compression chamber to open the valve to discharge fuel into the compression chamber.

5. In an internal combustion engine of the class described, means for feeding fuel to the engine cylinder including an injection plug and a compression plunger arranged co-axially therewith so as to form a compression chamber between the two of them communicating with the engine cylinder, said plug provided with an auxiliary fuel chamber communicating with the compression chamber through a relief valve and an auxiliary plunger to build up pressure in the fuel chamber to open the relief valve to establish communication with the compression chamber.

6. In an internal combustion engine of the class described, means for feeding fuel to the engine cylinder including an injection plug and a compression plunger arranged co-axially therewith so as to form a compression chamber between the two of them communicating with the engine cylinder, in combination with an auxiliary fuel chamber located within the plug and communicating with the compression chamber through an outlet controlled by a valve responsive to the pressure in the fuel chamber and a secondary plunger operable to compress the fuel in the fuel chamber sufficiently to open the valve controlling the outlet into the compression chamber.

7. In an internal combustion engine of the class described, means for feeding fuel to the engine cylinder including an injection plug and sleeve arranged end to end within a uniform tubular opening situated alongside the engine cylinder, a compression plunger mounted within the sleeve to form a compression chamber between the end of the plunger and the plug, said compression chamber communicating with the engine cylinder through a passageway controlled by the plunger.

8. Mechanism for injecting fuel into an engine cylinder comprising, in combination with said cylinder, a fuel-feeding plunger, a

- separate sleeve forming a cylinder for the plunger and formed with a passage into the engine cylinder, the plunger having a passage from its end which registers with the 5 passage through the sleeve at the end of the compression stroke of the plunger, and a separate plug at the end of the sleeve and cooperating with the sleeve and the plunger to define a compression space.
10. Mechanism for injecting fuel into an engine cylinder comprising, in combination with said cylinder, a fuel-feeding plunger and a separate sleeve forming a cylinder for the plunger and formed with a passage into the engine cylinder, the plunger having a 15 passage from its end which registers with the passage through the sleeve at the end of the compression stroke of the plunger.
10. Mechanism for injecting fuel into an engine cylinder comprising, in combination with said cylinder, a fuel compression chamber communicating with the cylinder, a compression plunger operable to compress fuel in the compression chamber and controlling the 20 communication with the cylinder, a fuel chamber communicating with the compression chamber through a fuel controlled passageway and a fuel plunger positioned co-axial to the compression plunger and operable to exert a pressure upon the fuel in the fuel chamber to open a valve leading into the compression chamber to discharge fuel thereinto.
11. Mechanism for injecting fuel into an engine cylinder comprising, in combination with said cylinder, a fuel compression chamber communicating with the cylinder, a compression plunger operable to compress fuel in the compression chamber and controlling the 25 communication with the cylinder, a fuel chamber communicating with the compression chamber through a fuel controlled passageway and a fuel plunger arranged co-axially to the compression plunger operable to exert pressure upon the fuel in the fuel chamber to open a valve leading into the compression chamber to discharge fuel thereinto, said fuel plunger and compression plunger operated in timed relationship and means 30 regulating the admission of fuel in the fuel chamber.
12. In an internal combustion engine having a main cylinder and a piston therein, means for feeding fuel to said cylinder including; a compression chamber having a plunger therein with means for actuating said plunger in proper time with respect to said piston, said plunger having a fuel depository in its end, means for trapping fluid 35 products of combustion in the compression chamber comprising intercommunicating axial and diametral bores in the plunger, and a passage between said cylinder and said chamber uncovered by the plunger for establishing communication between the passage and the 40
- axial bore at the end of the non-compression stroke of the plunger, a second passage between the cylinder and chamber, adapted to communicate with the diametral bore at the end of the plunger compression stroke, and 45 means for feeding fuel into said depository at the proper time before the end of the compression stroke of the plunger.
- In testimony whereof, I affix my signature.
